(57) **CLAIM**

The ornamental design for a bent suture needle, as shown and described.

DESCRIPTION

FIG. 1 is a perspective view of a bent suture needle, showing my new design;

FIG. 2 is a left side view of the bent suture needle shown in FIG. 1;

FIG. 3 is a right side view of the bent suture needle shown in FIG. 1;

FIG. 4 is a proximal end view of the bent suture needle shown in FIG. 1;

FIG. 5 is a distal end view of the bent suture needle shown in FIG. 1;

FIG. 6 is a top plan view of the bent suture needle shown in FIG. 1;

FIG. 7 is a bottom view of the bent suture needle shown in FIG. 1;

FIG. 8 is a perspective view of a bent suture needle, showing another embodiment of my new design;

FIG. 9 is a left side view of the bent suture needle shown in FIG. 8;

FIG. 10 is a right side view of the bent suture needle shown in FIG. 8;

FIG. 11 is a proximal end view of the bent suture needle shown in FIG. 8;

FIG. 12 is a distal end view of the bent suture needle shown in FIG. 8;

FIG. 13 is a top plan view of the bent suture needle shown in FIG. 8;

FIG. 14 is a bottom view of the bent suture needle shown in FIG. 8;

FIG. 15 is a perspective view of a bent suture needle, showing another embodiment of my new design;

FIG. 16 is a left side view of the bent suture needle shown in FIG. 15;

FIG. 17 is a right side view of the bent suture needle shown in FIG. 15;

FIG. 18 is a proximal end view of the bent suture needle shown in FIG. 15;

FIG. 19 is a distal end view of the bent suture needle shown in FIG. 15;

FIG. 20 is a top plan view of the bent suture needle shown in FIG. 15; and,

FIG. 21 is a bottom view of the bent suture needle shown in FIG. 15.
